HOUSE SIGN

Otto J. Ernst, Jr., Montague, Mich., assignor to Whitehall Metal Studios, Inc., Chicago, Ill., a corporation of Illinois

Application December 19, 1949, Serial No. 6,724

Term of patent 3½ years

(Cl. D1—12)

To all whom it may concern:

Be it known that I, Otto J. Ernst, Jr., a citizen of the United States, and a resident of Montague, in the county of Muskegon, and State of Michigan, have invented a new, original, and ornamental Design for a House Sign, of which the following is a specification, reference being had to the accompanying drawing, forming a part thereof, and in which:

Fig. 1 is a perspective view of a house sign, showing my new design; and

Fig. 2 is a perspective view of the opposite side thereof.

I claim:

The ornamental design for a house sign, as shown.

OTTO J. ERNST, JR.
